UNITED STATES PATENT OFFICE.

FRIEDRICH GEORG WINKLER, OF JERSEY CITY, NEW JERSEY.

PROCESS OF SIFTING GRANULAR MATERIAL.

SPECIFICATION forming part of Letters Patent No. 593,630, dated November 16, 1897.

Application filed August 14, 1896. Renewed April 15, 1897. Serial No. 632,345. (No specimens.)

To all whom it may concern:

Be it known that I, FRIEDRICH GEORG WINKLER, a subject of the Emperor of Germany, and a resident of Jersey City, Hudson county, State of New Jersey, have invented 5 certain new and useful Improvements in Processes of Sifting Granular Materials, of which the following is a specification.

This invention relates to a process of sifting 10 granular material—such as flour, meal, and other granular materials—through a sieve; and the process essentially consists in subjecting the said granular materials to the action of air-currents in the following manner: First, 15 the materials within the sieve are subjected to the action of a long and strong inward air-current, the volume and distribution of which are accurately controlled and which frees the particles which are adhering to the inside of 20 the sieve therefrom, and also brings large volumes of air into the sieve. Then immediately the materials are subjected to the action of a strong, sharp, and sudden outward current of air, which sifts the finer particles 25 through the sieve. This outward sifting-current is then followed by a long and strong outward after-current, which blows the sifted particles far from the sieve, so that such particles cannot be brought back by the next inward current. 30

I have found that the effective sifting of flour, meal, and other granular substances through a sieve or "bolting-cloth" requires that a large volume of air (much larger, in 35 fact, than that heretofore obtained) shall be made to pass both in and out of the sieve or bolting-cloth, the volume passing in and that passing out being of course equal, for in order to insure high sifting efficiencies sufficient air must be brought in to provide enough 40 for a very strong, swift, and sudden sifting impulse and also for a strong and long outward after-current, and if a large quantity of air is not brought in a sufficient supply for 45 such an outward after-current cannot be obtained without taking away some of the air that is needed for the strong sifting impulse. The air-wave must also be of such character as to act on or through the sieve in the following manner: First, there must be a strong 50 and long-continued inward current to provide the large quantity of air needed for the sub-

sequent outward currents; and also to clear the inside of the sieve of all particles of the material, and thereby prepare it for the succeeding sifting impulse; second, this inward current must be immediately followed by a strong, swift, and sudden outward sifting-current, which propels the fine particles of the material through the sieve; third, this sifting-current must be immediately followed by or continued into a prolonged and strong outward after-current to project the fine particles which passed through the sieve so far away that they cannot be caught by the next inward current. This outward after-current is indispensable, for if the first outward current is immediately followed by the next inward current more or less of the fine material which had passed through the sieve will be 70 carried back through, into, and upon the sieve, greatly reducing the output and impairing the efficiency of the apparatus.

It is desirable that the air-waves which generate the aforesaid currents through the sieve 75 shall be produced at comparatively low velocities of the fan or "pulsator," for high velocities—such, for example, as twelve hundred or fifteen hundred revolutions per minute—involve an excessive power cost and 80 wear and tear.

The attempts heretofore made to produce a commercial sifting apparatus have been unsuccessful, particularly in respect of the volume of air passed through the sieve and in 85 respect of the character of the air-waves and the velocities of the fan. So far as they have succeeded at all they have proceeded upon the principle of generating an air-wave that was intended to subject the material successively to the influence alternately of a relatively strong current of air moving outward through a small area of the sieve and a relatively weak current moving inward through a larger area of the sieve and following immediately upon the outward current; but in practice neither the relatively weak and long inward current nor the relatively short and strong outward current was ever obtained, because an air-cushion was produced between 90 the deflecting-grate and the sieve before the real sifting impulse began, which materially impaired the sifting effect. The result also of following up the sifting-current by the in-

ward current, without an intermediate outward after-current of considerable force and volume, was that a considerable part of the fine material that had just been sifted through 5 the sieve was carried back through, into, and upon the sieve, the output greatly reduced, and the action of the apparatus rendered very uncertain at moderate speed. This has compelled the employment of very high velocities, with consequent great power cost and 10 wear and tear, and even then the action has been uncertain, and to obtain a large sifting effect it has been necessary to employ comparatively long sieves and correspondingly 15 long pulsators and other parts. This has also greatly increased the power necessary to drive the machine, as well as the size and weight of the machine. Such apparatus was also constructed with cells open only toward the 20 periphery of the fan but closed inwardly and laterally. The consequence was the crowding of the incoming air and generation of return currents which shortened and then destroyed the inward current soon after it was 25 generated by creating a gentle outward current of the air which formed the aforesaid air-cushion between the deflecting-grate and sieve long before the intended short and strong outward sifting-current began to act 30 and lessened greatly the volume of air and the efficiency of the machine. These defects forced a resort to very high velocities in the attempt to develop proper inward volume and distribution of the currents; but the attempt 35 was unsuccessful, because the distribution of the air inside of the sieve was wrong in principle and could not be controlled. The process, however, which is the subject of the present application succeeds for the first time in 40 the art in the perfect control both of the incoming and the outgoing air-currents and also in bringing very large volumes of air into the machine, and I have been enabled to reduce the power cost both by a material reduction 45 in velocities of revolution and above all by the great reduction of the length of the sieve, fan, and other parts of the preferred form of machine by which the process is operated. These two facts combined have re- 50 sulted in so great a reduction of the power cost and wear and tear that my present invention attains an economy of operation never before approached.

While the present application relates to the 55 process by which the material is acted on by the air-currents, by whatever machine or device the same may be operated, I have also invented machines for working the process which I describe and claim in other applica- 60 tions.

In the first place the invention is the process of sifting flour and other granular substances through a sieve, which process consists in developing a strong inward current 65 of very great volume through the sieve, so as to clear it of all particles of the material and furnish the volume of air required for the fol-

lowing sifting and outward after-current, and then subjecting the material to the action of a powerful short and sudden outward sifting-current by which the fine particles are blown through the sieve, then following this immediately with a prolonged and strong outward after-current of large volume, which blows the sifted material to a distance from the 75 sieve. This process is preferably operated by an apparatus illustrated in the accompanying drawings, and which consists, essentially, of a sieve and outer deflecting-grate in proximity to the sieve and a plurality of pressure and vacuum generators independent of each other within the said outer deflecting-grate arranged concentrically to each other, so that the vacuums are developed in any succession determined upon and are regulated 80 to maintain the inward current practically up to the instant when the sudden sifting impulse begins to operate. The efficiency of this apparatus for operating the process depends upon the facts, first, that the machine 85 is so formed that there are open spaces in the interior which are connected together laterally in such manner that the total inward current or volume of air has sufficient room without generating return currents, which 90 would greatly reduce the volume of air and impair the effect of the inward current. Second, that the wave-generator contains or is combined with a plurality of vacuum-making devices arranged concentrically within and 95 successively behind each other, so that the inner vacuum-making devices successively act upon and increase or maintain the inward current previously generated almost up to the very instant when the next pressure 105 blade or device generates the next strong, swift, and sudden outward sifting-current. The strength and velocity of this sifting-current are greatly increased by the movement 110 in opposite directions of adjacent alternate inner gratings and inner pressure-blades, and especially by the construction of the apparatus in such manner that a part of the inward current which is developed and controlled by the successive vacuums rebounds or deflects 115 outward with immense velocity and powerful sifting effect. The intensity and force of this rebound are greatly increased by the afore- 120 said movement of the inner gratings in a direction opposite to the movement of the inner pressure-fans, for the effect of these opposite motions is that the incoming air is deflected and impelled in a direction opposite to that of the fan-blades which generate the sifting impulse, and the air encounters no resistance 125 until it is actually upon the said fan-blade. The consequence is an extremely powerful outward sifting impulse or current following almost immediately upon the stoppage of the inward current. Third, that the sifting-impulse generator is succeeded by blades or 130 groups of fans which generate a prolonged and strong outward after-current which projects the sifted material far from the sieve.

Fourth, that the wave-generator is so opened on the interior that the devices for said outward after-current get their air from the inward current, thereby preventing the crowding of the incoming air and aiding to maintain the inward currents. Fifth, that the air which passes from the inward currents to the outward after-currents, as aforesaid, sweeps under and keeps the inner surfaces of the 5 blades or fans thoroughly clean and prevents the accumulation of fine dust in the interior of the wave-generator.

Referring to the drawings which accompany the specification to aid in explaining how the process is operated, Figure 1 is a longitudinal vertical section of the preferred form of machine. Fig. 2 is a vertical cross-section on a larger scale and on the line 2 2 of Fig. 1. Fig. 3 is a vertical cross-section, 15 partly broken, on the line 3 3 of Fig. 1 and on the scale of Fig. 2. Fig. 4 is an elevation of the left end of Fig. 1. Fig. 4^a is a detail of the preferred device for driving the pulsator. Fig. 5 is a vertical section, on a large 20 scale, showing the preferred shape and relative positions of the gratings, suction-blocks, and fans. This figure illustrates parts of the same machine that is shown in Fig. 1. Figs. 6, 7, 8, and 9 are cross-sectional views 25 illustrating modifications in the arrangement of gratings, suction-blocks, and fans, but all arranged to operate the same process of sifting as does the machine shown in Fig. 1.

Referring to Figs. 1 to 5, inclusive, A is the bolting-chest, within which are arranged the sieve B, the concentric gratings C C' C² C³, the vacuum-generators or suction-blocks d d' d² d³, and the fans E E' E². Said sieve B may either revolve or be stationary. The 30 said gratings preferably revolve in the direction of the arrow y, Fig. 5—i. e., in the direction opposite to the revolution of the sieve B, if said sieve revolves—and the said suction-blocks and fans (which, taken together, 35 I term the "pulsators," since they produce the pulsations of the air which are instrumental in developing the currents and distribution of the volumes of air through the machine whereby the working of the process is effected) preferably revolve at comparatively 40 high velocities in the direction opposite to the revolution of the deflecting-grates. Said sieve B is a cylindrical reel having its peripheral wall formed of a suitable screen or 45 bolting-cloth stretched in any known and usual manner on frames 1 2, Fig. 2. At one end the said frames are fastened to rims 4, Fig. 1, carried on the ends of radial arms 5 5 of a circular head 6, Fig. 3, and the other end of 50 said frame is fastened to a circular head 7, which is bent and flanged at its outer part, as shown in Fig. 1. Openings 8 8 between said arms 5 5 permit the tailings to pass out to the discharge-chute W. A flanged rim 9 on said head 6 revolves with dust-tight fit in a circular groove 10, formed in the frame in the usual manner, and said head 6 carries a

hollow hub 11, which turns in boxes 12, carried by the frame. The hollow hub 15 of the head 7, and which is of sufficient diameter to 55 serve as the inlet for the material to be separated, turns in boxes 16 and makes a close working joint with the ends of the feed-chute X. G is a wire-mesh cylindrical basket carried by and revolving with said head 7. All 60 the said materials are required to pass through said basket, and any article or thing that is too coarse for the mesh of the basket will be retained thereby. Removable plugs 18 19 are provided to give access to said basket. 65

The aforesaid gratings are preferably arranged in concentric circles C C' C² C³, as shown in Fig. 5. The grates or bars of each circle are arranged in two parts or halves, one part being fastened to the head 20 and 70 the other part to the head 21, and, if desired, the number and shape of the bars in the one part may differ from those in the other part. The bars of the outer circle C are each preferably bent, as shown in cross-section, Fig. 75 5, to give the air-currents a direction approximately radially outward, and the bars of the inner circles of gratings C' C² C³ may be either curved, bent, or flat. The bars of said inner circles C' C² C³ extend from their respective 80 heads 20 or 21 nearly to the middle of the machine; but sufficient space is left between the inner ends of said bars to permit of the free revolution of the wings 25 25, Fig. 2, which carry the suction-blocks and fans. The bars 85 of the outer circle of deflecting-grates C, however, extend entirely across from the head 20 to the head 21, and said bars are preferably held in frames secured on said heads, as indicated in Fig. 1. 90

In the machine illustrated in the drawings all the gratings are of course driven from the same shaft or hub; but each circle of gratings may, if desired, be constructed so as to be driven independently of all the others. Referring to Fig. 1, the hollow hub 27 on head 20 passes through hollow hub 11 and turns in boxes 29, and the hollow hub 30 of head 21 passes through hollow hub 15, there being a good space between said hubs 30 and 15, and turns in boxes 32. A spiral conveyer 34 on hub 30 works the materials toward and into the aforesaid basket G. 105

The aforesaid suction-generators D D' D² D³ are preferably formed as blocks d d' d² d³, 110 which I term "suction-blocks" and which are preferably curved on their rear or suction side, as shown in Fig. 5. Said suction-blocks d d' d² d³ are arranged and fastened in the following manner on the wings 25 25, Figs. 1 115 and 2, which are fixed on the sleeve 35, that is keyed to the swift-running shaft K: Said wings 25 25 are provided with transverse arms 31, flanged at their outer ends, as shown. On said arms 31 are fastened the concentric rings 120 37 38 39 and the center plate 40. Said suction-blocks d d' d² d³ are each made in halves, 125 and said halves are fastened at opposite sides of said wings 25 25, respectively, between said 130 37 38 39 and the center plate 40. Said suction-blocks d d' d² d³ are each made in halves, and said halves are fastened at opposite sides of said wings 25 25, respectively, between said

wings and the aforesaid rings 37 38 39. The innermost suction-block d^3 is also made in halves, which are fastened on opposite sides of the wings 25 and between the same and 5 said center plates 40 40. Thus the several circles of gratings C' C² C³ are arranged and revolve between adjacent circles of suction-blocks and fans, and the several outer circles of suction-blocks and fans are arranged and 10 revolve between alternate circles of gratings, while the innermost circle of suction-blocks d^3 and fans 62 64 revolve inside of the innermost circle of gratings. (Compare Figs. 1 and 5.)

15 The aforesaid pressure-fans E E' E² are fastened to their respective rings 37 38 39. The outer fans E consist of main blades 45 45, which generate the swift, strong, and sudden sifting impulse in combination with the outer 20 deflecting-grate C, and said main fan-blades are bent forward at a considerable angle from the radius to effect the powerful outward rebound of the air-currents, which is a very important factor in generating the desired sudden and powerful outward impulse of the 25 sifting-current, as hereinbefore mentioned. Each of the said main blades 45 is followed by a group of auxiliary fan-blades, certain of which blades are preferably bent forward at 30 a less angle than the main fan-blades 45. The number of said auxiliary blades 48 may be increased or diminished according to circumstances, and said auxiliary blades are disposed between the main fans 45 and the advancing 35 side of the suction-blocks d . The purpose of said auxiliary blades 48 is to take up the air furnished by the inner fan-blades 55 57 and the front curve 60 of the suction-block d^3 and deliver it in a strong outward 40 after-current of large volume between said main fan 45 and the advancing face of said suction-block d . Said inner fan-blades 55 57 and curve 60 may each be either used singly, as shown, or be followed or even replaced by 45 groups of fan-blades, as indicated by reference to letter N, Fig. 6. The air delivered by said fans 55 57 and curved surface 60 to the auxiliary fans 48, and by said fans 48 sent through the sieve as a strong outward 50 after-current of large volume, blows the material which has been sifted by the main outward sifting-current which was developed by the main fans 45 so far from the sieve that it cannot be caught and brought back 55 by the next inward current. Said fan-blades 55 57 and curved surface 60 (or their corresponding groups of fan-blades) are so shaped and disposed in the machine as to provide the largest possible area for the outflowing 60 air and to offer the least possible resistance thereto. Therefore, as will be observed on inspection of the drawings, the passages between the fan-blades are preferably enlarged in the direction of the air-flow, and in this 65 manner not only does a large volume of air pass to the point of discharge of and form the outward after-current, but said air also pow-

erfully sweeps the under sides of the fan-blades and prevents the accumulation of fine particles of material in the interior of the machine. 70

Suction-blades 62 64, auxiliary to the innermost suction-block d^3 , may be fixed between the center plates 40 in any desired manner, or such auxiliary blades may be omitted and 75 the shape of the block d^3 correspondingly changed without affecting materially the result.

Any suitable driving-gear may of course be used, and I prefer the following arrangement: 80 A shaft 80, provided in the usual manner with fast and loose driven pulleys 80' 81, respectively, carries a cone 84 and driving-pulleys 85 86. A half-turn belt 88 from said pulley 85 drives a worm 90, which meshes with 85 a worm-gear 91 of the sieve B, thereby imparting a slow rotation to said sieve. A belt 95 from pulley 86 drives a pulley 98, fixed on the hub 27 of the gratings. A cone 100 is driven from cone 84 through the medium of 90 the shiftable endless belt 101, which is equipped with any suitable belt-shipper, and a pulley 102, fixed on the shaft 103 of said cone 100, drives pulley 105 on the aforesaid swift-running shaft K, on which are fixed, as 95 hereinbefore described, the "pulsators," (fans and vacuum - generators.) Thus by shifting belt 101 the speed of said fans and vacuum-generators may be varied according to the nature of the material without varying the speed of the sieve or the gratings. 100

The machine operates as follows: The material to be sifted having been fed through the chute X works into the basket G, and falling from thence is worked by the spiral 105 blade 75 into the annular space between the deflecting - grate and sieve. Now the long and strong inward air-current clears the sieve of adhering particles of the material and brings a large volume of air into the machine. 110 A certain proportion of this air is crowded upon and rebounds powerfully outward from the main fan-blades 45, developing a very strong, swift, and sudden outward current, which sifts the finer particles of the material 115 through the sieve. The remaining part of the in brought air flows freely into the interior of the machine, as described, and to the auxiliary fans 48, between the said main sifting-fans 45 and the front side of suction-blocks d , and is here expelled as a long and strong outward after-current, blowing the sifted particles far from the sieve. Then follows the next inward current, and so the cycle repeats itself continuously all around 120 the sieve. The aforesaid inward and outward currents may be considered to be due to the crests of high pressure and the hollows of low pressure of an air-wave of peculiar nature, which is produced by my apparatus and propelled around the sieve, a wave which I believe to be essentially unlike any heretofore generated in sifting-machines. 125

As hereinbefore stated, the process which

is the subject of my present application is not limited to any particular form of apparatus, and the apparatus herein shown and described are only used as illustrations of good forms of machines for operating the process. Said machines are not herein claimed, but are severally the subject of claims in other of my applications for patents of the United States.

10 In Figs. 6, 7, and 8 I have shown modifications of the arrangements of the gratings, fans, and vacuum-generators.

In Fig. 6 I employ only two suction-blocks $F' F^2$, preferably shaped as shown, and only 15 two gratings $J' J^2$. L is the main fan to generate the sifting impulse, M the auxiliary fans to generate the outward after-current, and N inner blades which coöperate with the grating J^2 to deliver the air to the said auxiliary fans M . $O' O^2$ are auxiliary suction-blades fixed on the heads which carry the blocks $F' F^2$. The air-currents generated by this machine agree in their general character with those generated by the machine illustrated in Figs. 1 to 5 and operate the same process of sifting.

In the machine shown in Fig. 7 I employ only one set of suction-blocks F^3 and one deflecting-grate J^3 . L' is the main fan; M' , the 20 auxiliary fans for aiding in generating the outward after-current, as hereinbefore described. $P P$ are blades revolving in the same direction as the deflecting-grate J^3 and either driven from the same hub or separately, 25 as desired. I now prolong the suction-blocks F^3 backwardly by plates f^3 , as shown, whereby I increase and prolong the inward current, and in coöperation with said blades $P P$ prevent the injurious action of the return currents hereinbefore referred to.

The machine shown in Fig. 8 is analogous to that shown in Fig. 7; but I now replace the blades P by the grating P' , which revolves in the same direction as deflecting-grate J^3 45 and may be driven from the same hub or separately, as desired, and the bars of said grating P' may be wider than shown in any desired degree. Both these machines generate substantially the same air-wave as the machine shown in Figs. 1 to 5 and operate the same process.

Fig. 9 illustrates a cross-section of the preferred machine, wherein the arrangement of pulsators is in general similar to that of Fig. 5. It differs, however, from the last-named

machine in two respects. First, the suction-blocks $d^6 d^7 d^8 d^9$ are lengthened out, as shown, to effect the control of the volume and distribution of the air referred to above, and, second, the center of the machine is open between the inner suction-block and the hub, with only a single grating between said suction-block and hub. The opening in the center was also shown in Fig. 8, and the machines of Figs. 8 and 9 both demonstrate the 60 fact that the use of pockets or cells open only toward the periphery, but closed toward the center, which were an essential characteristic of all machines that have been heretofore known as "wave-generators," is not essential 65 in my new machines.

Thus comparison of Figs. 5 to 9, inclusive, proves that my process is, as before stated, independent of any special machine and depends upon the generation in any manner of 70 suitable air-currents and the subjecting to such currents of the materials to be sifted in the manner hereinbefore described. In each of said figures I have indicated the direction of the air-currents and approximately their 75 strength by arrows on one-half the figures. The distribution of the air-currents is the same on the other half of the figures, but the arrows are there omitted to permit clear representation of the parts of the machines. 80

Now, having described my improvements, I claim as my invention—

The process of sifting granular materials hereinbefore described, consisting in first clearing the sieve by long and strong inward 90 currents of air of large volume, then propelling a part of this air in a strong, swift and sudden blast outward through the sieve, whereby the finer particles of the material are sifted through the sieve, and following 95 this blast with a long and strong outward after-current of the remainder of the air whereby the sifted particles are blown far from the sieve and out of reach of the next inward current, and causing said several currents to 100 travel successively over all parts of the sieve.

In testimony that I claim the foregoing as my invention I have signed my name, in presence of two witnesses, this 12th day of August, 1896.

FRIEDRICH GEORG WINKLER.
